UNITED STATES PATENT OFFICE.

HUGO G. TOMICH, OF CHICAGO, ILLINOIS, ASSIGNOR TO RELIANCE MANUFACTURING COMPANY, OF CHICAGO, ILLINOIS, A CORPORATION OF ILLINOIS.

SEWING MACHINE.

Application filed February 9, 1924. Serial No. 691,593.

This invention relates to sewing machines, and particularly to sewing machines of the type employing a double needle bar.

In sewing machines employing two needle bars, it is desirable to provide means whereby one of the needle bars may be released from the other and maintained in inoperative elevated position while a corner is being turned. It has been found, however, that unless the means for locking the needle bars together and for maintaining the one needle bar in its elevated position are simply and strongly made, the device is liable to become disarranged due to the stresses produced by the rapid vibratory motion of the needle bars.

It is the object of the present invention to provide simple and durable means for locking the two needle bars together and for maintaining one of the needle bars in elevated inoperative position.

It is believed the invention will be understood most readily from a detailed description thereof taken in connection with the accompanying drawings, in which

Figure 1 is a view of the sewing machine head looking at the face plate and parts carried thereby;

Figure 2 is a section through the sewing machine head substantially on the line 2—2 of Figure 1;

Figure 3 is a side view of the sewing machine head and part of the sewing machine arm, as viewed from the left in Figure 1;

Figure 4 is a plan view of the sewing machine head and a portion of the arm;

Figure 5 is a view similar to Figure 1 but showing the cover plate removed so as to disclose the locking means of the present invention;

Figure 6 is a view similar to Figure 5 but showing the locking member in the position it assumes when one of the needle bars is to be retained in inoperative position;

Figure 7 is a perspective view of the locking member, and

Figure 8 is a perspective view of an arm fixed to one of the needle bars and to which, in turn, is connected the pitman for causing the vibratory motion of the needle bars.

Referring now to the drawings, in which like characters indicate like parts in the several views, 10 indicates the sewing machine head having therein the upper and lower

bearings 11 and 12 respectively. Arranged 55 for reciprocatory motion through the bearing 12 is the hollow needle bar 13, and slidably arranged in the bearing 11 and also through the center of the hollow bearing 13 is the needle bar 14 which is preferably a 60 solid cylindrical member.

Fixed to the needle bar 14, in any desired manner, is the arm 15, shown in detail in Figure 8. The arm 15 is provided with a bore 16 through which the needle bar 14 65 passes. The arm is also provided with a circular downwardly extending portion 17 which is spaced from the bar 14 so as to permit one side of the hollow needle bar 13 to reciprocate within the space between the arm 70 17 and the bar 14. Arm 17 at the lower end thereof is provided with a laterally extending pin 18 to which is pivotally joined one end of the pitman 19, the other end of the pitman being rotatably mounted on the pin 75 20 which is eccentrically mounted on the machine drive shaft 21 rotatably mounted in the machine arm 22. The outer end of the pin 18 is provided with an anti-friction collar 23 which is positioned in the slot 24 of the 80 frame in order to guide the lower end of the arm in its reciprocatory motion.

Extending outwardly from the side of the hollow bar 13 is a lug 25 which passes through the opening 26 in the locking or 85 latching arm 27 (see Figure 7). The lug also passes through the slot 28 in the machine face plate 29 so that rotary motion of the hollow bar 13 is prevented.

Pivotedly mounted in the head on the 90 fixed pivot 30 is a dog 31, which is adapted to co-operate with the lug 32 on the locking or latching member 27 in order to maintain the hollow needle bar in its upper inoperative position. A spring 33 is provided 95 which normally tends to move the upper end of the dog 31 to the right, as viewed in Figures 5 and 6. The dog 31 adjacent to the upper end thereof is provided with a recess 34 adapted to receive the lug 32 on the bar 27 when said bar is rotated in a counter-clockwise direction, as viewed in Figures 5 and 6. The locking arm 27 is also provided at the upper end thereof with an internal recess or offset 35 adapted when said locking member is rotated in a clockwise direction, as seen in Figures 5 and 6, to engage the lug 36 on the arm 15 (see Figures 5 and 100 105 105

8) in order to lock the two needle bars together.

The locking member 27 is provided with a pin 37 which projects through a slot 38 in the link or lever 39 pivotally supported on the face plate 29 by means of the screw 40. The upper end of the lever 39 is guided by means of the screw 41 which passes through the arcuate slot 42.

10 A link 43 has one end pivotally joined to the lever 39 by means of the screw 44. The other end of the link 43 is joined to one arm of the bell crank lever 45 by means of the screw 46. The other arm of the lever 45 is joined through the medium of the link 47 (see Figures 3 and 4) to one arm of the bell crank lever 48, the other arm of lever 48 being joined to one arm of the operating lever 49 through the medium of the link 50. A 15 spring 51 is provided which tends normally to force the link 50 upwardly, link 47 to the left, as seen in Figures 3 and 4, and link 43 to the right, as seen in Figure 1. In this position, the notch 35 of the locking member 27 is arranged to engage the lug 36 on the arm 15 to lock the two needle bars together, as above explained.

When it is desired to release the hollow needle bar and retain it in its elevated inoperative position, the operator will press upon the lever 49, as by her knee, causing the upper end of the locking member 27 to move to the left, as seen in Figures 5 and 6. This will move the notch 35 from engagement 30 with the lug 36, but will cause the lug 32 to move into a position where it will be engaged by the notch 34 in the dog 31, thus releasing the hollow needle bar from the other one and locking it in elevated position.

40 This operation of releasing one of the needle bars from the other is found greatly to facilitate the turning of corners.

It will thus be seen that applicant has provided for locking the needle bars together or for holding one of them in inoperative position by the use of the minimum number of simple and durable parts.

50 While in the drawings and in the above description, applicant has disclosed but a single embodiment of his invention, it is to be understood that certain modifications are contemplated, and the invention, therefore, should be limited merely by the scope of the appended claims.

Having thus described my invention, what I claim as new and desire to secure by Letters Patent of the United States is:

60 1. A sewing machine comprising a head, a pair of needle bars slidably mounted in said head, a lug projecting from one of said needle bars, a slotted locking member pivotally joined to the other of said needle bars, said locking member being provided with an interior notch or recess at one end of the

slot therein, the notch being arranged to receive said lug to lock said needle bars together when said locking member is moved to one position, a shoulder on said locking member, and a shoulder stationary relative to the reciprocating movement of said needle bars adapted to be engaged by the shoulder on said locking member when the latter is moved to a second position.

2. A sewing machine comprising a head, a pair of needle bars slidably mounted in said head, a lug projecting from one of said bars, and a locking member pivotally joined to the other of said bars for swinging movement in a substantially vertical plane, said locking member being provided with a slot in which said lug is positioned and having a notch or recess at one side of said slot, and communicating therewith, arranged to receive said lug to lock said bars together.

3. A sewing machine comprising a head, a pair of slidably mounted needle bars, a lug projecting from one of said bars, a slotted locking member pivotally joined to the other of said bars, said locking member having a notch or recess at one end of the slot therein, said recess being arranged to receive said lug to lock said bars together, a dog, and means on said locking member arranged to co-operate with said dog to maintain said other of said bars in elevated position.

4. A sewing machine comprising a head, a pair of needle bars slidably mounted in said head, a lug projecting from one of said bars, a locking member pivotally joined to the other of said bars, said locking member having a slot within which said lug is positioned and having a notch or recess at one side of said slot and communicating therewith adapted to receive said lug to lock said bars together, a dog, and means on said locking member arranged to co-operate with said dog to maintain said other of said bars in elevated position.

5. A sewing machine comprising a head having spaced bearings, a hollow needle bar slidably mounted in one of said bearings, a second needle bar slidably mounted in the other of said bearings and said hollow needle bar, a lug projecting from said second needle bar, a locking member pivotally joined to said hollow needle bar, said locking member being provided with an L-shaped slot arranged to receive said lug to lock said needle bars together.

6. A sewing machine comprising a head having spaced bearings, a hollow needle bar slidably mounted in one of said bearings, a second needle bar slidably mounted in the other said bearing and said hollow needle bar, a lug projecting from said second needle bar, a locking member pivotally joined to said hollow needle bar, said locking member having a slot within which said lug is positioned, and a recess at one side of said

slot and communicating therewith adapted to receive said lug to lock said needle bars together.

7. A sewing machine comprising a head having spaced bearings, a hollow needle bar slidably mounted in one of said bearings, a second needle bar slidably mounted in the other of said bearings and said hollow needle bar, a lug projecting from said second needle bar, a locking member pivotally joined to said hollow needle bar, said locking member being provided with an L-shaped slot adapted to receive said lug to lock said needle bars together, a dog, and means on said locking member arranged to co-operate with said dog to maintain said hollow needle bar in elevated position.

8. A sewing machine comprising a head having spaced bearings, a hollow needle bar slidably mounted in one of said bearings, a second needle bar slidably mounted in the other said bearing and said hollow needle bar, a lug projecting from said second needle bar, a locking member pivotally joined to said hollow needle bar, said locking member having a slot within which said lug is positioned, a recess at one side of said slot and communicating therewith adapted to receive said lug to lock said needle bars together, a dog, and means on said locking member arranged to co-operate with said dog to maintain said hollow needle bar in elevated position.

9. A sewing machine comprising a head, a pair of needle bars slidably mounted in said head, a locking member pivotally joined to one of said needle bars, means on the other of said needle bars arranged to co-operate with said locking member to lock said bars together, a pin projecting from said locking member, a lever pivotally supported on said head provided with a slot through which said pin projects, and means for shifting said lever to move said locking member into and out of locking position.

10. A sewing machine comprising a head, a pair of needle bars slidably mounted in said head, a locking member pivotally joined to one of said bars, means on the other of said bars adapted to co-operate with said locking member to lock said bars together, a dog, means on said one of said needle bars co-operating with said dog for maintaining said one of said bars in elevated position, a pin projecting from said locking member, a lever pivotally mounted on said head, said lever having a slot through which said pin projects, and means for shifting said lever to move said locking member from one to the other of its operative positions.

11. A sewing machine comprising a head, a pair of needle bars slidably mounted in said head, a lug projecting from one of said

needle bars, a locking member pivotally supported on the other of said needle bars, said locking member having a slot within which said lug is positioned and having a notch communicating with said slot adapted to receive said lug to lock said bars together, a pin projecting from said locking member, a lever pivotally supported on said head and having a slot through which said pin projects, and means for shifting said lever.

12. A sewing machine comprising a head, a pair of needle bars slidably mounted in said head, a lug projecting from one of said needle bars, a locking member pivotally supported on the other of said needle bars, said locking member having a slot in which said lug is positioned and a recess communicating with said slot adapted to receive said lug to lock said bars together, a dog, means on said locking member arranged to co-operate with said dog to maintain said other of said needle bars in elevated position, a pin projecting from said locking member, a lever pivotally supported on said head, said lever having a slot through which said pin projects, and means for shifting said lever to move said locking member from one to the other of its locking positions.

13. A sewing machine comprising a head having spaced bearings, a hollow needle bar slidably mounted in one of said bearings, a second needle bar slidably mounted in the other of said bearings and said hollow needle bar, a lug projecting from said second needle bar, a locking member pivotally supported on said hollow needle bar, said locking member being provided with a notch adapted to receive said lug to lock said bars together, a dog, means on said locking member co-operating with said dog arranged to maintain said hollow needle bar in elevated position, a pin projecting from said locking member, a lever pivotally supported on said head and having a slot through which said pin projects, and means for shifting said lever to move said locking member from one to the other of its operative positions.

14. A sewing machine comprising a head having spaced aligned bearings, a hollow needle bar slidably mounted in one of said bearings, a second needle bar slidably mounted in the other said bearing and said hollow needle bar, a lug projecting from said second needle bar, a locking member pivotally joined to said hollow needle bar, said locking member having a slot within which said lug is positioned and a recess at one side of said slot and communicating therewith arranged to receive said lug to lock said bars together, a dog, means on said locking member adapted to co-operate with said dog to maintain said hollow needle bar in elevated position, a pin projecting from said locking member, a lever pivotally supported on said head, said lever having a slot through which

said pin projects, and means for shifting said lever to move said locking member from one to the other of its operative positions.

15. A sewing machine, comprising a head, a pair of needle-bars slidably mounted in said head, a latching member pivotally connected to one of said needle-bars for reciprocation therewith, said latching member being pivoted on a substantially horizontal axis for swinging movement in a vertical plane, said latching member having a slot with a recess in one wall of said slot, a lug on said latching member, a shoulder on the other of said needle-bars engaging in said slot and receivable in said recess, a shoulder, stationary relative to the reciprocations of the needle-bars, mounted on said head and adapted to engage the lug on said latching member, and means for swinging said latching member to engage one or the other of said shoulders.

16. A sewing machine comprising a head, a pair of needle bars slidably mounted in said head, a longitudinally slotted latching member pivotally connected to one of said needle bars for reciprocation therewith, said latching member being pivoted for swinging movement in a substantially vertical plane, said latching member having a shoul-

der projecting therefrom and the slot thereof having a recess at one end thereof, a moving shoulder carried by the other of said needle bars, a shoulder stationary relative to the motion of said needle bars, one of said last-named shoulders engaging in said slot, and means for swinging said latching member to engage and disengage said shoulders.

17. A sewing machine comprising a head, a pair of needle bars slidably mounted in said head, a latching member pivotally connected to one of said needle bars for pivotal movement in a substantially vertical plane, said latching member having a longitudinal slot therein provided with a lateral recess at one end of said slot, a lug projecting from the other of said needle bars and playing in said slot, a shoulder projecting from said latching member, a shoulder stationary relative to the reciprocating movement of said needle bars adapted to be engaged by the shoulder on said latching member, and means for swinging said latching member to bring said lug into said recess or to bring said shoulders into cooperating engagement.

In witness whereof, I hereunto subscribe my name this 5th day of February, 1924.

HUGO G. TOMICH.
